(57) **CLAIM**

The ornamental design for an clipboard, as shown and described.

DESCRIPTION

FIG. 1 is a front, top perspective view of the clipboard showing my new design;

FIG. 2 is a top, side perspective view of FIG. 1;

FIG. 3 is a back elevation view of FIG. 1;

FIG. 4 is a top plan view of FIG. 1;

FIG. 5 is a right side elevation view of FIG. 1;

FIG. 6 is a bottom plan view of FIG. 1;

FIG. 7 is a left side elevation view of FIG. 1;

FIG. 8 is an inverted front elevation view of FIG. 1;

FIG. 9 is a front, top perspective view of Figure with the light bridge swiveled into an upright position; and,

FIG. 10 is a front, top perspective view of FIG. 1 with the door to the storage box in a partially open position.

The broken lines showing features of the clipboard in FIGS. 1, 2, and 4 through 10 are included for the purpose of showing portions that form no part of the claimed design.
